VACUUM CLEANER CART

Clarence D. Reece, Duluth, Minn., assignor to
Car-Ree-All Products, Inc., Minneapolis, Minn.

Application April 24, 1948, Serial No. 23,049

3 Claims. (Cl. 15—257)

1

This invention relates to a new and useful improvement in utility conveyances and more particularly to a wheeled carry-all for supporting portable vacuum cleaners.

There are now on the market certain vacuum cleaners which are made to slide on the floor or to be carried by a handle. When slid on the floor the usable length of hose is shortened as the cleaning attachment is usually carried about waist high. When the cleaner is carried by hand, only one hand is available for manipulating the attachments. This invention comprehends the furnishing of a novel cart which supports the vacuum cleaner in an upright position. The use of the cart permits the use of both hands for the manipulation thereof.

Another object constitutes the provision of an ambulatory cart which is so balanced that it is maintained substantially in the upright position and remain stationary and which may be tilted slightly to enable locomotion.

The invention consists in certain novel combination and arrangements of parts as will herein-after be more fully set forth in the claims. In the accompanying drawings, there has been illustrated one complete example of the physical embodiment of the invention wherein the parts are combined and arranged according to the best mode that has thus far been devised for the practical application of the principles of the invention.

In Figure 1 is a side elevational view of the vacuum cleaning cart;

Figure 2 is a front elevation of the same;

Figure 3 is a perspective view of the vacuum cleaning cart;

Figure 4 is a perspective rear view of the cleaning cart;

Figure 5 is a view of the handle with portions broken away;

Figure 6 illustrates a modified form of a base and handle securing means;

Figure 7 is a view of the disassembled cleaner support members; and

Figure 8 is a view with parts broken away of modified form of spreader bar and end of member 34.

Referring to the drawings in detail, handle 10 has on the upper end thereof hand grip member 11. The handle 10 is removably secured to member 12, which member constitutes a handle attaching means. Mounted in the lower part of member 12 is axle 14 which has on the outer ends thereof rotatably mounted wheels 16 and 18. It is generally preferred that these wheels be provided with rubber tires. Secured to member 12

2

and extending outwardly therefrom is cleaner support base member 20 which terminates in the leg 22. Generally, it is preferred that this leg be provided with a rubber shoe or the like 24 which prevents abrasion of the floor surface. Mounted on member 20 are vacuum support members 26 and 28. These are secured to the base members 20 by a suitable bolt 29 and wing nut 30. Secured to the handle 10 and formed as shown in Figure 1 is stair guide member 32, which is secured to the base by bolt 29 and wing nut 30. This enables the cart to be taken up and down stairways with comparable ease and without damage to such stairs. For supporting the vacuum cleaner and for holding the attachments, a member shown generally at 34 is removably secured to the handle 10. In the upper and the lower ends of the member 34 are shown supporting and spread bars 36 and 38. Passing through these bars and the handle are bolts 40 and 42 which are held in place by wing nuts 44 and 46. The stair guide member 32 is secured to the handle by the bolt 42 and the wing nut 44. The member 34 can be made of any suitable materials, such as cloth, canvas, or the like. This member 34 is provided with the vacuum support pocket 48 which holds the upper end of the vacuum cleaner while the other end rests in members 26 and 28. Pockets 50, 51, 52, 53 and 54 are for receiving and holding attachments of the vacuum cleaner. The attachment to be placed in pocket 54 has the upper end thereof supported in loop member 56. A pocket 58 is provided on the rear of the member 34 for receiving the vacuum hose and cord.

In Figure 6 is shown a modified form of vacuum cleaner supporter base member, in which member 60 is formed integral with the base member 20 and the handle 10 fits over the member 60 and is removably secured thereto by any suitable means such as cotter pin 62. In Figure 7 is shown the vacuum support members 26 and 28 before being assembled. In Figure 5 is shown the upper end of the handle 10 which consists of two parts, the upper part being so arranged as to slide over the other part so that during shipping, the handle may be disassembled. This also permits the adjusting of the height of the handle to a suitable height for the operator.

In Figure 8 is shown a modified form of spreader bar 64 which has one side at least made of spring steel, and this side has groove 66 formed therein. The canvas or like material 68 is folded over a cord 70, and this cord is sewn in the upper end of the canvas 68. This enables the cord to be slipped into the groove 66 and provides easy

means of attaching the member 34 to the supporting handle 10.

From the drawing and the descriptions it is apparent that there has been provided a wheeled cart that is useful in supporting a vacuum cleaner in the upright position when the cleaning is going on and also to support the cleaner when stored.

What I claim is:

1. A vacuum cleaner cart consisting of a longitudinally extending base of greater length than width and said base having an axle receiving opening in one end and the opposite end of the base being turned downwardly to provide a rigid supporting leg, a vacuum cleaner supporting means mounted on the base intermediate the ends thereof, a handle attaching means on the base adjacent the end having the axle receiving opening therein, an upwardly extending handle removably secured on the handle attaching means, an axle mounted in the axle receiving opening in the base, wheels mounted on the axle, a single stair guide member having one end attached to the handle adjacent the lower end and extending outwardly and downwardly therefrom and the other end of the stair guide member being attached to the base, said stair guide extending along the opposite side of the handle from the side nearest the vacuum cleaner support means, means on the handle for holding the vacuum cleaner parallel to the said handle. 25

2. A vacuum cleaning cart comprising a base of greater length than width, said base having an axle receiving opening adjacent one end and the opposite end of the base being turned downwardly to provide a supporting leg, vacuum cleaner supporting means mounted on the base, a handle attaching means on the base adjacent one end thereof, an upwardly extending handle removably secured on the handle attaching means, an axle mounted in the axle receiving opening, wheels 40

mounted on the said axle, and a single stair guide member having one end attached to the handle and extending downwardly and outwardly therefrom and the other end attached to the base, said 5 stair guide means extending along the side of the handle opposite the side of the handle nearest the vacuum cleaner support means.

3. A vacuum cleaner cart comprising an elongated one-piece base of considerably greater length than width with one end bent downwardly for a support, said base having an axle receiving opening adjacent the end opposite the downwardly bent end, an axle in said axle receiving opening, wheels mounted on said axle, a handle operatively connected to the base, means attached to the handle for holding a vacuum cleaner mounted on the base in an upright position, and stair guide means attached to the base and extending rearwardly from the base and then upwardly and attached to the said handle on the opposite side of the handle from which the means for holding a vacuum cleaner in upright position is attached.

CLARENCE D. REECE.
